UNITED STATES PATENT OFFICE.

FRANK R. HENRY, OF ST. LOUIS, MISSOURI.

DESIGN FOR A STOVE OR RANGE WARMING-OVEN.

46,340.

Specification for Design.

Patented Sept. 1, 1914.

Application filed July 6, 1914. Serial No. 849,293. Term of patent 14 years.

To all whom it may concern:

Be it known that I, FRANK R. HENRY, a citizen of the United States of America, residing in the city of St. Louis, State of Missouri, have invented a new, original, and ornamental Design for a Stove or Range Warming-Oven, of which the following is a specification, reference being had to the accompanying drawing, forming part thereof.

The figure is a perspective view, showing my new design.

I claim—

The ornamental design for a stove or range warming oven, as shown.

FRANK R. HENRY.

Witnesses:

E. K. CLARK,

A. J. McCUALEY.
